UNITED STATES PATENT OFFICE.

JOHN J. McAVOY, OF SEATTLE, WASHINGTON.

DESIGN FOR A WATCH-FOB.

59,244.

Specification for Design.

Patented Oct. 4, 1921.

Application filed January 30, 1920. Serial No. 355,199. Term of patent 3½ years.

To all whom it may concern:

Be it known that I, JOHN J. McAVOY, a citizen of United States, and a resident of Seattle, in the county of King and the State of Washington, have invented a new, original, and ornamental Design for Watch-Fobs, of which the following is a specification, reference being had to the accompanying drawings, forming a part thereof.

In the drawings, Figure 1 is a plan view

of the watch fob, showing my new design. Fig. 2 is an edge view of Figs. 1 and 3. Fig. 3 is a plan view of the obverse side of Fig. 1. Fig. 4 is a sectional view taken upon the line $x-x$ of Fig. 1.

I claim:

The ornamental design for a watch fob, as shown.

JOHN J. McAVOY.
